UNITED STATES PATENT OFFICE.

CLINTON E. DAVISON, OF LITTLE ROCK, IOWA.

VENDING-MACHINE.

No. 857,037.

Specification of Letters Patent.

Patented June 18, 1907.

Application filed April 17, 1906. Serial No. 312,189.

To all whom it may concern:

Be it known that I, CLINTON E. DAVISON, a citizen of the United States, residing at Little Rock, in the county of Lyon and State of Iowa, have invented certain new and useful Improvements in Vending-Machines; and I do hereby declare that the following is a full, clear, and exact description of the same, reference being had to the annexed drawings, 5 making a part of this specification, and to the letters and figures of reference marked thereon.

The object of my invention is to provide a vending machine of such construction that 15 its operation will be reliable when the proper coin is placed in the machine, and which, more especially, is adapted for vending flat articles such as envelopes and letter paper, etc., but in stating this particular object I do 20 not intend to exclude myself from its use or adaptation, or of any part of it, for any purpose to which the same may be put.

Figure 1 is a perspective view of a vending machine embodying my invention; Fig. 2 a 25 vertical section from front to rear; Fig. 3 a horizontal section on line 3—3 of Fig. 2; Fig. 4 a detail view, in section, of a portion of the mechanism for causing the delivery of a single article; Fig. 5 a detail perspective view of 30 the wheel part of said mechanism; Fig. 6 a like view and a section of the upper end of the shaft for the wheel shown in Fig. 7; Fig. 7 a detail view in perspective of the end of the 35 coin-releasing lever which coacts with said wheel; Fig. 8 a detail perspective view of the coin-operated brake for the motor; Fig. 9 a like view of a portion of one of the article-supporting leaves or hinged plates and its 40 latch device; Fig. 10 a perspective view of the clamp for holding the coin-locking and releasing levers when the motor driver latch-releasing device is to be returned to its starting 45 position.

The casing A of my machine may be made 50 of wood or metal, and is of such form as is best suited for its purpose, and hung within it is a vertical series of pivoted plates or leaves B, each of which is adapted to receive and support the article to be vended by the machine, such for example, a sheet of paper, or 55 an envelop and a sheet of paper. Said plates or leaves are duplicates, and they are pivoted at the back of the machine between the sides of the casing A, by horizontal rods C that pass through eyes b on the rear edges of the respective leaves and project at opposite sides

thereof where they engage bearings in plates a fastened to the casing sides. Said bearings consist of slots a' in the plates a which extend from one edge thereof inward and downward, so that the rods may readily slide into place and will remain there. The back of the casing A is hinged to form a door to give access to the interior for the placing therein of the leaves with the articles to be vended, and a suitable lock is provided to permit access only by an authorized person. The leaves B are supported in a horizontal position, with the articles to be vended resting thereon, by latch mechanism, which upon 60 the introduction into the machine of a proper coin, releases a leaf at a time, which by gravity thereupon swings downward on its pivot and delivers the article to an inclined board or shelf D at the bottom of the casing A, 65 where it may be removed through an opening in the front of the casing. The lowermost leaf strikes at its free front edge against and is arrested in an inclined position by said shelf, but the successively released leaves 70 fall at their free end against the previously released leaf.

The front ends of the leaves when they are in a horizontal position, reach quite to the front wall of the casing A, and in said front 75 wall there is a vertical slot a² into which projects a tongue b' on each leaf, and engaging the underside of said tongue there is a latch E that consists simply of an L-shaped elastic or spring wire or rod, one arm e of the latch 80 being fastened between a pair of vertical bars or posts F on the front wall of the casing, the latch being thereby mounted or held in place so that its other arm e', which is free, may be moved to and from leaf-engaging position, it 85 normally, by the spring action of the wire or rod, tending to move and remain in such position. To guide the latch in its movements, as well as support it under the weight of its leaf, I provide a vertical bar G which I fasten 90 to the front wall of the casing A opposite the vertical slot a², which bar has a hole or opening g for each free arm e' of the latch, through which it plays, and it has a right-angled flange g' with a notch g² in its free edge 95 through which the other arm e of the latch passes and plays. At one side the leaf tongue has a downwardly turned lip or lug b². Between the bar G and the vertical series of latch arms e there is a vertical threaded shaft 100 or screw H, and mounted on said shaft is a latch-engaging and releasing device that con-

sists of a plate or bar I having preferably two threaded lugs or nuts i which engage the screw, so that by the revolution of the screw the bar I is moved vertically. The lugs or nuts i bear against the bar G so that they will be prevented from turning with the screw when it revolves and thereby be compelled to travel vertically. At its upper end the bar has an inclined surface i' which, as the 5 bar moves along by the action of the screw, will engage the latch arm e and cam or press the latter horizontally in the direction to withdraw the end of the arm e' from beneath its leaf B to release the latter. At its lower 10 end the latch-engaging bar has a similar inclined surface to enable the bar to readily pass the latch arms when, after having moved to the top of the series of latch rods and released the top-most one, it is returned to the 15 bottom again, as is hereinafter described, ready for another ascent.

It will be observed that my leaf latches and their releasing mechanism are extremely simple in construction and certain to operate properly and are not liable to derangement.

The screw H is journaled at its top in a bearing conveniently provided in the bar G, and at its bottom in the top plate of the 30 frame of a spring motor K which, through a train of gears, drives or rotates the screw to cause the upward travel or ascent of the latch-releasing bar I. At its lower end, the screw has a pinion h which meshes with a 35 gear L on the upper end of a shaft M, which through a train of gears, not necessary to be described, receives motion from the motor spring in a well-known way. The gear L is loose on its shaft M, for a purpose hereinafter 40 described, and it is coupled to or uncoupled from its shaft, at will, by means of a small bar m pivoted at one end in a vertical, diametrical slot in the shaft end, and adapted to be moved into or out of engagement with a 45 radial slot l in the hub of the gear. When the bar is in engagement with the hub slot, the wheel is coupled to the shaft so that they rotate together, and when it is out of engagement with the hub slot, the wheel may 50 revolve independently of the shaft. A flat spring m' interposed between the bar and the bottom of the shaft slot yieldingly holds the bar in either of its positions relative to the hub slot.

55 The motor is kept from operating by a brake or stop device consisting of a disk N that bears on the side of a gear wheel O of the motor, and said disk is carried on the lower end of a vertically movable rod n which is 60 guided in openings in the motor frame, and which at its upper end is pivotally connected to one end of a lever P pivoted between its ends to a bracket k on the top plate of the motor frame, its other end being in the path of a 65 coin passing through a coin chute or guide Q,

supported by an arm q'. Rolling on its edge from the guide or chute, the coin encounters and rests upon the lever end and by its weight rocks the lever to lift the brake disk from contact with the gear wheel O and thereby frees 70 the motor, and so long as the coin remains on the lever, the motor is free to run, and the coin is thus kept on the lever by an overhanging lip or tongue q inclining downward from the delivery end of the chute, for a period only long enough to let the motor run sufficiently to cause the latch releasing bar I to move far enough to release a single latch to free its leaf B, and at the expiration of such period of time the coin is removed from the 80 lever and the latter being then free, is rocked to re-engage the brake disk or shoe with the gear wheel O. To free the lever P from the coin, there is a second lever R also pivoted between its ends to the bracket k, 85 one end of which lever R overhangs a horizontal lug or projection p' on the lever P near its coin-engaging end, which overhanging end of the lever R, when it is depressed, engages said lug and carries downward the coin-engaged end of the lever P, and thus frees the 90 coin from the chute lip q, and it then falls into a box S. To enable the lever P to be thus operated, its portion adjacent its coin-engaged end is made of thin steel or other elastic metal. 95 The lever R is operated to produce the action just described by having its opposite end r engaged by a radial pin t on the outer periphery of a rim or flange T on the gear wheel L, said end r of the lever R being inclined so 100 that by the engagement and passage beneath it of said pin, that end of the lever R will be raised and the other end depressed. A spring r' acts on the lever R to restore it to normal 105 position after having been operated, as described, by the pin t. There are preferably several pins t on the wheel flange, because the occasion for the operation of the lever R occurs oftener than once in one revolution of the gear wheel L. Although, of course, this 110 is a mere matter of timing the parts of the mechanism. A post or stud k' rising from the top plate of the motor frame contiguous to the end r of the lever R, prevents any accidental lateral displacement of the lever by 115 the pressure of the pin t thereon.

When the latch releasing bar I has reached the upper limit of its travel and is to be returned to the bottom of the screw, the motor is locked from operation by a locking lever U 120 pivoted to the top plate of the motor frame, which is swung to place its end in engagement with the tooth of one of the wheels of the gear train; the two levers P and R are rocked so that the end r of the lever R is taken out of the path of the pins t and held there, (which may be done by the device V shown in Fig. 10), and the bar m is turned to place it out of engagement with the hub slot l, thus freeing the gear wheel L from its shaft, M. By applying 125

a key to the squared upper end of the screw H, the latter may now be turned backward, and the latch-releasing bar thereby be made to travel downward, whereupon, on reaching 5 its lowermost position, the bar m is moved to re-engage the hub slot, the levers P and R are released, and the locking lever U moved out of engagement with the motor gear, and the machine is again ready for use.

10 A small, supplemental casing A' for the latch-mechanism is hinged to the front of the machine, which may be opened when desired to give access thereto to the motor mechanism and to the money box, a suitable lock being provided to prevent its being opened except by some authorized person.

15 The operation of my machine is as follows:—If the machine is to vend stationery, say a sheet of letter paper and an envelop, to 20 be sold for one cent, the back door of the casing A being opened, the leaves B are removed, save the bottom one, and a sheet of paper and an envelop placed on the bottom leaf, which is, of course, first latched in a horizontal position, then, one after another, the remaining leaves B are placed in position and latched, a sheet of paper and an envelop being laid on each as fast as they are put in position. The leaves are spaced the proper distance apart 25 by means of the lips b², so that the operator need not pay any special attention to get their tongues b' in proper position on top of the springs e'. A cent being dropped through the casing coin slot a³, it will fall into 30 the coin chute or guide Q and roll on edge down the same until it strikes the chute lip q and rests on the lever P, which it will depress, thus lifting the brake shoe N from the gear wheel O and starting the motor. The screw 35 H will now be revolved, and feed the latch releasing bar I upward carrying its inclined or beveled upper end into contact with the arm e of the latch and gently pressing the latter sidewise will withdraw its arm e' from beneath a leaf, whereupon the leaf will swing 40 downward to an inclined position and deliver the stationery to the inclined shelf D, whence it will slide to the mouth or opening at the front of the casing A, in reach of the purchaser.

45 By the time the bar I has traveled far enough to release a leaf, one of the radial pins i on the gear wheel rim T will engage and lift the end r of the lever R rocking its opposite end downward, which, being in engagement with the coin-engaged elastic end of the lever P, will press such end downward and release the coin, whereupon said lever P will be moved to move the brake shoe into contact with the wheel of the motor train, and 50 thus the latter will be stopped, and the machine be in readiness for another operation. When the latch-operating bar I has reached the limit of its upward travel, its return to the bottom of the series of latches is effected in 55 the manner hereinbefore described.

The device V is used, as shown in Fig. 10, by slipping its forked or split end over the arm q' with its other end overlying and pressing down the levers P and R.

It will be understood that, to embody my 70 invention in a machine for delivering articles costing more than a cent, it is necessary merely to alter the proportions of the coin slot, chute, and coin-actuated lever.

Having thus described my invention, what 75 I claim is:—

1. The combination of a coin chute having at its delivery end a downwardly inclined over-hanging lip, a movable coin-operated lever or device having an integral independently operable, movable coin-engaging member disposed beneath said lip and means to actuate said member to release a coin therefrom. 80

2. The combination of a coin chute having at its delivery end a downwardly inclined 85 over-hanging lip, a movable coin-operated lever or device having an integral elastic, independently operable, movable coin-engaging member disposed beneath said lip, and means to actuate said member to release a 90 coin therefrom.

3. The combination of a coin chute having at its delivery end a downwardly inclined over-hanging lip, a movable coin-operated lever or device having an integral independently operable, movable coin-engaging member disposed beneath said lip, a motor, and 95 motor-actuated means to actuate said member to release a coin therefrom.

4. The combination of a coin chute having 100 at its delivery end a downwardly inclined over-hanging lip, delivery mechanism, a movable coin-operated lever or device having an integral independently operable, movable coin-engaging member disposed beneath 105 said lip, and means to actuate said member to release a coin therefrom.

5. The combination of a coin chute having at its delivery end a downwardly inclined over-hanging lip, delivery mechanism, a 110 movable coin-operated lever or device having an integral independently operable, movable coin-engaging member disposed beneath said lip, a motor, and motor-actuated means to actuate said member to release a coin 115 therefrom.

6. The combination of a coin chute having at its delivery end a downwardly inclined over-hanging lip, a coin-operated lever, a coin releasing lever having one end disposed beneath said lip and engaging the coin-operated lever, means to prevent lateral displacement of the coin releasing lever and means to actuate the coin-releasing lever. 120

7. The combination of a coin chute having 125 at its delivery end a downwardly inclined over-hanging lip, a coin-operated lever, a coin-releasing lever having one end disposed beneath said lip and engaging the coin-operated lever, means to prevent lateral dis- 130

- placement of the coin releasing lever, a motor controlled by the coin-operated lever, and motor-operated means to actuate the coin-releasing lever.
5. 8. The combination of a coin guide having at its outlet end a lug or projection, a lever having an elastic portion contiguous to said outlet end and disposed beneath said projection, and means to operate the elastic portion of the lever contiguous to said outlet end.
9. The combination of a coin guide having at its outlet end a lug or projection, a lever having an elastic portion contiguous to said outlet end and disposed beneath said projection, a motor controlled by said lever and motor-actuated means to operate the elastic portion of the lever contiguous to said outlet end.
10. The combination of a coin guide having at its outlet end a lug or projection, a lever having an integral elastic member contiguous to said outlet end and disposed beneath said projection, and means to operate the portion of the lever contiguous to said outlet end.
11. The combination of a coin chute having at its delivery end a downwardly inclined over-hanging lip, a coin-operated lever or device, a coin-releasing lever engaging the latter beneath said lip, and a pin-carrying wheel the pin of which is constructed to engage and lift one end of and to actuate said coin-releasing lever.
12. The combination of a motor, a coin chute having an overhanging lip inclined downwardly from its delivery end, a pivoted coin operated lever, an independently pivoted coin releasing lever, a lug on the coin operated lever overhung by the end of the coin releasing lever, and means acting on the other end of the coin operated lever to move the same on its pivot.
13. The combination of a motor, a coin chute having an overhanging lip inclined downwardly from its delivery end, a pivoted coin operated lever, an independently pivoted coin releasing lever, a lug on the coin operated lever overhung by the end of the coin releasing lever, means acting on the other end of the coin operated lever to move the same on its pivot, and means for holding the coin releasing lever out of the path of said means.
14. The combination with the coin operated lever having a lug near its coin-engaging end, and a coin-releasing lever, and an arm parallel therewith, of a member engaged at one end with said arm and its other end pressing down said levers.
15. The combination with a coin operated lever having a lug near its coin engaging end and a coin releasing lever having one end overhanging said lug, an arm parallel with the end of the coin engaging lever, and a forked member having its forked end engaging over said arm, and its other end overlying and pressing down said levers.

In testimony whereof I affix my signature in presence of two witnesses.

CLINTON E. DAVISON.
